(76) Inventor: **Tammy Russelli**, 1857 S. Washington St. Apt 111C, Naperville, IL (US) 60565-2456

Primary Examiner—Sandra L. Morris
(74) Attorney, Agent, or Firm—Clifford Kraft

(**) Term: **14 Years**

(57) **CLAIM**

(21) Appl. No.: **29/176,914**

The ornamental design for a combined child's game and game pieces, as shown and described.

(22) Filed: **Feb. 27, 2003**

DESCRIPTION

Related U.S. Application Data

(63) Continuation-in-part of application No. 29/156,156, filed on Feb. 22, 2002, now abandoned, which is a continuation-in-part of application No. 29/134,425, filed on Dec. 20, 2000, now abandoned.

The design is a child's game of pieces where the pieces are picked up as other pieces are tossed. The design includes a bag for hold the pieces and the pieces themselves. The design is not embedded into any other article.

(51) **LOC (7) Cl. 21-01**

FIG. 1 is a perspective view of the combined child's game and game pieces, showing my new design;

(52) **U.S. Cl. D21/386; D21/300**

FIG. 2 is an elevational view thereof, the game pieces shown removed for ease of illustration;
